Harry G. Balthazar,

Hugh H. Wagner
A. M.

UNITED STATES PATENT OFFICE.

HARRY G. BALTHASAR, OF ST. LOUIS, MISSOURI, ASSIGNOR TO B. AND B. MANUFACTURING COMPANY, OF ST. LOUIS, MISSOURI, A CORPORATION OF MISSOURI.

WHISTLE.

Application filed March 8, 1920. Serial No. 363,920.

To all whom it may concern:

Be it known that I, HARRY G. BALTHASAR, a citizen of the United States, residing at the city of St. Louis, in the State of Missouri, have invented certain new and useful improvements in Whistles, of which the following is a specification.

This invention is a whistle for motor-vehicles, and belongs to what is known as the compression-type of whistle, being operated from the compression in one of the cylinders 10 in the engine, instead of from the exhaust.

Its especial advantages are cheapness in manufacture, facility in cleaning, ease in operation, and reliability.

In the accompanying drawings forming part of this specification, in which like numbers of reference denote like parts wherever they occur,

20 Figure 1 is a side elevation showing the whistle attached to a cylinder-head, in the place of an ordinary priming-cup, such priming-cup being removed for that purpose;

25 Figure 2 is a front elevation;

Figure 3 is a sectional view on the line 3—3 in Figure 2;

Figure 4 is a detail of a plate for adjusting the volume of sound from the whistle; 30 and

Figure 5 shows a modification, in which a pair of slidable members is used.

By the threaded nipple 1, this device, as a whole, is attached to the cylinder-head 2. 35 For the sake of convenience, this may be by removing one of the priming cups, but, if desired, may be through a separate hole.

The operating cord 3 leads to the driver's seat, and may, if desired, be attached to the steering-post (not shown) or at any other 40 suitable point. At its other end, the said cord is fastened in the hole 4 in the bell-crank 5, pivoted at 6 to lugs 7 projecting from the valve-casing 8.

45 The gas passes out of the cylinder through passage 9 into chamber 10, the wall of which on one side is provided with valve-seat 11 opposite hole 12 normally closed by the hexagonal nut 13.

50 Valve 14 seats upon valve-seat 11 and controls the exit of gas from chamber 10.

Valve 14 is kept normally closed by spring 15 or any other suitable spring, and is opened by the pressure of nose 16 of bell-crank 5

when the said bell-crank 5 is rocked on pivot 55 6 by a pull upon the cord 3.

When valve 14 has thus been opened, the gas rushes through opening 17 into chamber 18 and thence through the restricted port 19 and past the throat 20 of the whistle. Throat 60 20 is formed in a hollow casting 21, which, for the sake of easier casting, is formed with the opening 22. Opening 22 is closed by a cap 23 by upsetting the edge 24 of the said cap. 65

Nut 13 is easily removable for the purpose of cleaning chamber 10 or passage 9 or for the purpose of taking out valve 14 for re-grinding or for the purpose of cleaning valve-seat 11. 70

Member 21 is formed with a flange 25, preferably internally screw-threaded. Valve-casing 8 is provided with a collar 26, preferably externally screw-threaded, which screw-threads on collar 26 and within flange 25 serve to unite valve-casing 8 and hollow member 21 together. The order of the screw-threading of the said parts may be reversed or other means of union of the two parts provided. 75

The plate 27 contains the slot 28, and is attached by the screw 29 to the member 21. It may be attached to the casting 21 either on the outside, as shown in the drawings, or upon the inside thereof, as not shown in the drawings, or, as further not shown in the drawings, it may be fastened in a groove in the wall of casting 21. Another form not shown in the drawings, but which may be substituted for the slot and screw, is a 85 90 groove and screw. For the slidable member 27, a pivoted member (not shown in the drawings) may, likewise, be substituted, which member will swing like a trap-door. 95

The slot 28 allows the plate 27 to be adjusted in either direction, so as either to reduce the opening of the throat 20 or to make it larger, with the object of regulating the volume of tone emitted by the whistle, either to suit the taste of individual users or 100 to accommodate the same to the amount of compression in the individual engine or cylinder to which this whistle is attached.

The modified form shown in Figure 5 consists of a pair of wings 30 and 31, slidably pivoted by the screw 32 to the casting 21. 105 This allows even more accurate adjustment of the size of the opening through throat 20.

If desired, both wings 30 and 31 can be closed, as shown in Figure 5, or one of them may be partly or entirely open and the other one partly or entirely closed. The combination of these wings admits of innumerable permutations of arrangements for small or large apertures, and permits nice adjustment to suit any taste or requirement. It, also, prevents the possibility of hissing through slot 28. The device shown in Figure 5 can be located either inside or outside of the casting 21 or in a groove in the same.

Having thus described this invention, I hereby reserve the benefit of all changes in form, arrangement, order, or use of parts, as it is evident that many minor changes may be made therein without departing from the spirit of this invention or the scope of the following claims.

20 I claim:

1. A whistle of the compression type having a whistle throat and co-operating plates adjustable over the throat opening to vary the extent of the same.

2. A whistle of the compression type having a whistle throat and a pair of co-operating plates having joint and separate adjustment over the throat opening to vary the extent of the same.

3. A whistle of the compression type having a whistle throat and a pair of superimposed co-operating plates having an opening-and-closing movement with respect to the throat opening for varying the extent of the same.

4. In a whistle of the compression type, the combination with a casting having attachment to an engine cylinder and provided with a whistle throat, of a pair of pivotally mounted co-operatively arranged plates having adjustment over the throat opening and being capable of a relatively open-and-shut movement permitting innumerable permutation of arrangement for small or large openings.

In testimony whereof I hereunto affix my signature.

HARRY G. BALTHASAR.
